WEIGHING SCALE FOR A COMPUTING SYSTEM

Edward C. Karp, 1001 Lincoln Ave., Belvidere, Ill.

Filed Feb. 14, 1964, Ser. No. 78,636

Term of patent 14 years

(Cl. D52—10)

FIG. 1.

FIG. 2.

FIGURE 1 is a perspective view from the front of the weighing scale for a computing system;

FIGURE 2 is a side elevational view of the weighing scale;

FIGURE 3 is a front elevational view of the weighing scale; and

FIGURE 4 is a rear elevational view of the weighing scale.

The undisclosed side of the scale is substantially the same in appearance as the side shown.

I claim:

The ornamental design for a weighing scale for a computing system, as shown and described.
